UNITED STATES PATENT OFFICE.

WILLIAM H. WEEKS, OF PHILADELPHIA, PENNSYLVANIA.

CHARGING MECHANISM FOR COATING CONFECTIONERY.

SPECIFICATION forming part of Letters Patent No. 637,053, dated November 14, 1899.

Application filed July 14, 1899. Serial No. 723,800. (No model.)

To all whom it may concern:

Be it known that I, WILLIAM H. WEEKS, a citizen of the United States, residing at Philadelphia, in the county of Philadelphia and 5 State of Pennsylvania, have invented certain new and useful Improvements in Charging Mechanism for Coating Confectionery, of which the following is a specification.

My invention relates to charging mechanism for coating confectionery, and has for its object the rapid placing of the cores, centers, or forms to be coated into the receptacles wherein they are placed preparatory to their immersion into the coating solution, thereby 15 increasing the output of goods for a given amount of labor and the consequent decrease in cost.

I attain the objects of my invention by the mechanism illustrated in the accompanying 20 drawings, in which—

Figure 1 is a plan view. Fig. 2 is a front view in readiness for loading, partially broken to show the cores in suspension; Fig. 3, a front view when discharging the cores, partially 25 broken to show the dropped cores; Fig. 4, an end view in readiness for loading; Fig. 5, a partial end view when delivering its load; Fig. 6, an enlarged plan view of a part of one of the tipping plates. Fig. 7 is a view of a 30 core as received and held by the tipping plates. Fig. 8 is a view of a core as being delivered by the tipping plates. Fig. 9 is an enlarged end view of the tipping plates. Fig. 10 is a modification of means for holding the tipping 35 plates.

Similar characters of reference refer to similar parts throughout the views.

My mechanism has an outer rectangular case formed of sides 12 and ends 34. Above 40 ends 34 are secured removable caps 56, held by screws 7 to ends 34, which extend upward to a flush height with sides 12. Between ends 34 and caps are openings 8 circular in shape and forming bearings for tipping plates 9. 45 Tipping plates 9, having journals 10, are secured in openings or bearings 8, as seen in Figs. 1 to 5, inclusive. The plates 9 have at their edge opposite journals 10 semicircular openings or notches 11, and their outer ends 12 50 are carried beyond the case ends 34 and caps 56 and are formed to a curved inclined shape 13, tending from the openings 14, which are

cut away to clear case ends 34 and caps 56 toward their extreme ends 15, and are also rounded upon their lower or underside, as seen 55 at 32, Figs. 4, 5, and 9. The tipping plates 9 are placed in pairs within the case, journaled in openings 8 and with their notched edges toward each other, but enough removed from each other to permit them to swing down 60 freely and without interference. At the outer sides of ends 34 of the case are supports 16 17, secured for swinging movement by hinges 18, which are also secured to case ends 34, and when in the position shown in Figs. 2 and 4 hold 65 the plates 9 flat, as seen in Figs. 1, 2, and 4. The supports are held in their upright position, as seen in Fig. 2, by rods 19 20, which are connected to lever 21, fulcrumed at 22 and controlled by tension-spring 30, the lever 21 70 extending upwardly beyond the rod connection and then bent outward at 24.

In some sizes of my mechanism I do not put supports at each end of the tipping plates, but only at one end. 75

My case is placed upon any suitable bench, table, or support, and guides 24' 25 are attached to the said support and provide a means by which the operator controls the case when in the act of loading and also dis- 80 charging.

To operate my mechanism, the attendant introduces into the case above plates 9 a deemed sufficient number of cores, centers, or forms 26, which the mechanism will receive for one operation and which are to be placed in the receptacle for immersion into the coating solution, and they naturally fall on plates 9 in a promiscuous mass. The operator now works the case in the direction 90 controlled by guides 24' 25 and by short sudden moves and quick reversing shakes the cores about, which movements in a very short time cause a majority of the cores to enter the openings formed by the notches 11, 95 leaving only a very small proportion to be placed by hand, and thus greatly economizing the time over the hand method heretofore employed. When the openings 11 are filled with cores supported as seen in Figs. 1, 2, and 7 the operator places the case over the dipping-receptacle 27 and against stops 28 to place the cores 26 exactly over the pockets in the receptacle. Then by moving lever 21 100

to the position shown in Fig. 3 supports 16 17 will be turned down, tipping plates 9 will roll on their bearings 10, their near edges 29 will roll down, as seen in Figs. 3, 5, and 8, and the cores 26 will be released to drop into the pockets of receptacle 27. Pressure upon lever 21 now being released the spring 30 will force all the moving parts to their normal position in readiness for reloading, as seen 5 in Figs. 1, 2, 4, and 7. The rounded surface 32 and edge 13 of plates 9 and the rounded surface 31 of supports 16 17 provide the means for easy and frictionless replacing of plates 9 after their dropping. Side 1 is of less depth 10 than side 2, as seen at 33, to allow my mechanism to pass freely over the dipping-receptacle 27.

In Fig. 10 I show a modification in which a flat spring 34 is attached to end 3^a of the case 20 and holds support 16^a in an upright position, except when the support is pressed against by the operator, when the spring yields and allows the support 16^a and tipping bars 9^a to drop, but forces support 16^a and tipping bars 25 9^a to their normal loading position upon the removal of the operator's pressure. This modification is used in some instances, as in small mechanisms, where it is unnecessary to provide the means to support a heavy 30 charge.

I claim—

1. In a charging mechanism, a case, and journaled therein tipping plates, in pairs, and at their outer or opposite edges, means 35 formed on and in the plates to receive and support cores, centers or forms between them, means to support the plates, and means to remove the supports and tip the plates, in manner substantially as set forth.

2. In a charging mechanism, a case having 40 bearings formed therein, at the ends, caps over the bearings, multiple pairs of tipping plates journaled in the bearings, means

formed on the plates to receive cores, centers or forms for coating, means to support 45 the plates and the cores, centers or forms thereby held, and means to tip the plates for unloading and return them to their original position for reloading, in manner and form substantially as set forth. 50

3. In a charging mechanism, a case having bearings, multiple pairs of tipping plates journaled in the bearings, means formed on and in the plates to support forms for coating, portions of each plate, opposite each 55 journal, removed to free the plates from contact with the case, a part of each plate extending beyond the part removed as aforesaid, and exterior to the case, curved and rounded surfaces for the ends, yielding supports curved and rounded at their point of contact with the plates, means to secure the supports for upward and downward swinging, means to release the supports and drop the plates and thereafter replace the supports and force the plates to their load receiving or charging position, substantially 60 as set forth.

4. In a charging mechanism, a case, and supported therein multiple tipping plates, in 70 pairs, journaled upon the opposite edges of each pair, means to support the plates in flat position for charging, means to guide the case for forward and backward movements, means to stop the case at a predetermined 75 position, and means to simultaneously tip each pair of plates and discharge the charge between and below them, in manner and form substantially as described.

In testimony whereof I affix my signature 80 in presence of two witnesses.

WILLIAM H. WEEKS.
